FIG. 1

FIG. 2

INVENTOR.
J. L. PARENTICE

BY

A. J. Dowell
ATTORNEY

UNITED STATES PATENT OFFICE

157,412

COVERED JUG

Jess L. Parentice, Zanesville, Ohio, assignor to
Shawnee Pottery Company, Zanesville, Ohio, a
corporation of Ohio

Application January 13, 1948, Serial No. 143,684

Term of patent 3½ years

(Cl. D44—21)

To all whom it may concern:

Be it known that I, Jess L. Parentice, a citizen of the United States of America, residing at Zanesville, in the county of Muskingum and State of Ohio, have invented a new, original, and ornamental Design for Covered Jug, of which the following is a specification, reference being had to the accompanying drawing, forming a part thereof, wherein:

Fig. 1 is a perspective view of a covered jug, showing my new design;

Fig. 2 is another perspective view showing the opposite side; and,

Fig. 3 a top plan view thereof.

I claim:

The ornamental design for a covered jug, as shown.

JESS L. PARENTICE.
